UNITED STATES PATENT OFFICE.

AUGUST J. SCHMIDT, OF CHICAGO, ILLINOIS, ASSIGNOR TO DIAMOND WHIP COMPANY,
OF CHICAGO, ILLINOIS, A CORPORATION OF ILLINOIS.

WHIP.

1,157,424.

Specification of Letters Patent. Patented Oct. 19, 1915.

Application filed May 19, 1915. Serial No. 29,032.

To all whom it may concern:

Be it known that I, AUGUST J. SCHMIDT, a resident of Chicago, in the county of Cook and State of Illinois, have invented certain 5 new and useful Improvements in Whips, of which the following is a full, clear, and exact description.

The invention relates to whips in which the lash is rotatably connected to the handle. 10 In whips of this character, a rotatable connection which is simple in construction is desirable, and in some instances it is desired to provide a connection in which all of the metallic parts adjacent the rotatable connection are covered.

One object of the invention is to provide a whip, including a simple rotatable connection between the whip-lash and the handle and which is constructed so that the strands 20 of the whip-lash can be extended around the connection.

The invention consists in the several novel features hereinafter set forth and more particularly defined by claims at the conclusion 25 hereof.

In the drawings: Figure 1 is a perspective of a whip embodying the invention. Fig. 2 is a longitudinal section. Fig. 3 is a perspective of the metallic parts in separated 30 relation.

The improved whip-handle comprises a metallic stem or rod 5 provided with an integral head 6 at its outer end, a point 7 at its inner end and an annular shoulder 8 integral therewith. The handle-stem, including the shoulder 8 thereon, is covered with leather, as at 9, to provide a suitable gripping-surface and the head 6 and outer end portion are covered by braided strips 10 to 35 provide means for preventing the handle from slipping out of the user's hand.

A screw-thread 11 is formed on the stem adjacent the outer end of the point 7 and a collar 12 is threaded to fit on said screw-thread to longitudinally confine a sleeve 14 on the stem between the shoulder 8 and said collar. The inner end of screw-thread 11 terminates at a point where it will limit the 45 rotation of collar 12 and will act as a shoulder to prevent the collar from being jammed between the shoulder 8 and the collar, so that the sleeve will be longitudinally confined but rotatable on the stem. Furthermore, when the collar is screwed firmly 50 against the inner end of the screw-thread

11, it will be secured against rotation. A whip-lash 15, usually formed of strands of leather braided together, is tightly braided around the sleeve 14, as at 16, and a piece of leather 17 is interposed between the braided 60 lash-portion 16 and the sleeve 14. Adjacent the inner end of sleeve 14, the whip-lash and the sheath 17 are wrapped, as at 18, to secure them on the sleeve. The sheath 17 and the whip-lash extend loosely around collar 65 12 and around point 7. The sheath between the whip-lashing and the metallic portions of the whip prevents the metallic parts from wearing the lash. In use, the whip-lash, sheathing and sleeve 14 are free to rotate 70 relatively to the handle, for a purpose well understood in the art.

In assembling the device, the strands of the whip-lash are braided around the sheath, so that both the strands and sheath will be 75 secured to sleeve 14. The sheath and the strands of the lash inwardly of the sleeve are left open and then the sleeve is slipped on the stem. By folding back the unsecured or open portion of the sheath and unbraided 80 portion of the lashing, the collar 12 can be screwed into the position shown in Fig. 2 to rotatably hold the sleeve on the handle. Next, the whip-lashing will be tightened or braided around the sheathing and point 7, 85 the sheathing being left loose around the point and said collar, so that the lash will be free to rotate. The point 7 prevents the lash from being bent sharply adjacent the handle when it is being cracked, to avoid 90 breaking the lash.

The invention exemplifies a whip in which the whip-lash is rotatably connected to the head, which is simple in construction and can be produced at a low cost, and in which 95 the lash is extended to entirely cover the rotatable metallic sleeve of the rotatable connection; also one in which the point 7 may be integrally formed with the handle stem and in which only a single adjustable 100 collar is necessary.

The invention is not to be understood as restricted to the details set forth, since these may be modified within the scope of the appended claims, without departing from the 105 spirit and scope of the invention.

Having thus described the invention, what I claim as new and desire to secure by Letters Patent, is:

1. In a whip, the combination of a han- 110

dle-stem, having an integral shoulder and a point thereon, a collar on and formed separately from the stem and held thereon adjacent the inner end of the point, a sleeve 5 rotatably held on the stem between the collar and said shoulder, and through which the point can pass longitudinally in placing the sleeve on the stem, and a whip-lash secured to and rotatable with said sleeve, said 10 collar being movable into position to hold the sleeve on the stem after the sleeve has been placed on the stem.

2. In a whip, the combination of a handle-stem, having an integral shoulder and a point thereon, a collar screw-threaded to the stem adjacent the inner end of the point, a sleeve rotatably held on the stem between the collar and said shoulder, and a whip-lash 15 secured to and rotatably held with said 20 sleeve.

3. In a whip, the combination of a handle-stem, having an integral shoulder and a point thereon, a collar on and formed separately from the stem and held thereon adjacent the inner end of the point, a sleeve 25 rotatably held on the stem between the collar and said shoulder, and through which the point can pass longitudinally in placing the sleeve on the stem, and a whip-lash comprising strands braided around and covering 30 said sleeve, said collar being movable into position to hold the sleeve on the stem after the sleeve has been placed on the stem.

4. In a whip, the combination of a handle-stem, having an integral shoulder and a point thereon, a collar on and formed sepa- 85

rately from the stem and held thereon adjacent the inner end of the point, a sleeve 40 rotatably held on the stem between the collar and said shoulder, and a whip-lash comprising strands secured around said sleeve and extending loosely around said collar and point, said collar being movable into position to hold the sleeve on the stem after the sleeve has been placed on the stem. 45

5. In a whip, the combination of a handle-stem, having an integral shoulder and a point thereon, a collar on and formed separately from the stem and held thereon adjacent the inner end of the point, a sleeve 50 rotatably held on the stem between the collar and said shoulder, and through which the point can pass longitudinally in placing the sleeve on the stem, a whip-lash having strands secured to and braided around said 55 sleeve, and a sheath between said sleeve and said lash, said collar being movable into position to hold the sleeve on the stem after the sleeve has been placed on the stem.

6. In a whip, the combination of a handle-stem, having an integral shoulder and a point thereon, a collar screw-threaded to the stem adjacent the inner end of the point, a sleeve 60 rotatably held on the stem between the collar and said shoulder, a whip-lash secured to said sleeve, and a sheath also secured 65 to said sleeve.

AUGUST J. SCHMIDT.
